CONTACTING APPARATUS

Edwin R. Broden, Pittsburgh, Pa., assignor to
Blaw-Knox Company, Pittsburgh, Pa., a corporation of New Jersey

Application September 29, 1939, Serial No. 297,125

3 Claims. (Cl. 183—14)

The present invention relates generally to contacting apparatus for effecting intimate contact between a liquid and a gas for the purpose of removing dust or mist or some chemical constituent from the gas or for adding some substance to the gas which is contained in the liquid. More particularly, it relates to an improved apparatus for effecting intimate contact between the gas and liquid and for removing any entrapped liquid from the gas after it has been brought into contact with the liquid. The invention is particularly applicable to gas cleaning and hence will be described hereinafter as so applied.

As is well known by those skilled in this art, cleaners of the character to which the present invention relates are placed in gas delivery and distribution lines for the purpose of eliminating impurities from the gas. Gas pressures prevailing in such lines vary over quite a wide range and hence it is necessary to provide a variety of cleaners in order to take care of the different pressure conditions encountered and the different capacities required. By the present invention I eliminate the necessity of having such a large variety of cleaners. This is accomplished by the provision of a cleaning unit or cartridge which may be of the same construction regardless of the pressure of the gas to be cleaned and which is mounted in a shell or container of sufficiently rugged construction to take care of the gas pressures to be encountered. Assuming that cleaners having a given capacity are desired for installations utilizing different gas pressures, one type of cartridge can be utilized for all such installations, it being necessary only to select an outer shell or container which is sufficiently rugged to withstand the pressure to be encountered in any particular installation.

In some distribution systems it is not necessary to have pipe lines or the apparatus connected to them capable of resisting more than approximately 50 pounds pressure per square inch while in other cases the pressure may exceed this considerably. In small distribution systems of a character to which the present invention is particularly applicable, the pressures encountered may run from lower than 50 pounds per square inch to approximately 500 pounds per square inch. As the part of the apparatus which actually cleans the gas is not subjected to great differences in pressure that portion of the apparatus may be standardized so that it may be used in systems in which the gas pressures may vary over a wide range. By providing a cleaner which is remov-

able as a unit from the outer shell or container it is only necessary to change the shell for different installations. In commercial practice one shell may be made sufficiently heavy to withstand 50 pounds pressure, another 250 pounds pressure, another 500 pounds pressure and these three different strengths of outer shell will be sufficient to adapt the entire apparatus to practically any range of pressure likely to be encountered in an ordinary distribution system.

Of course in any installation in determining the size of shell to be used the volume of gas to be delivered as well as the pressures will be taken into consideration. The higher the pressure the denser the gas and with a given velocity of flow a greater weight of gas will pass through the pipe line and the cleaner at a given velocity in a given time. If the gas is highly compressed the capacity of the cleaner in cubic feet of gas per second will be substantially the same as if the gas is at a low pressure but the total weight of gas or the total quantity of gas as it is delivered to the consumer at a lower pressure will be greater in a cleaner of given size the greater the pressure.

The cleaner which I provide is particularly well adapted for installation in pipe lines of moderate size such as lines 1 to 2 inches or slightly larger in diameter although it may be used in much larger installations. Where very large pipe lines are equipped with gas cleaners, however, it is preferable to adopt some other form of construction to more conveniently handle the large quantities of gas. The cleaner which I provide may be installed in any gas line merely by cutting a small section out of the pipe and by applying the necessary connections to the cleaner. As a general rule, when the cleaner is installed in a pipe line, valves are also installed to make it more convenient to disconnect the cleaner or to bypass the flow of gas around the cleaner whenever it is necessary to replenish the contacting liquid. As the provision of such pipe connections and valves is within the skill of those employed in this art such subject-matter forms no part of the present invention and is not disclosed in the preferred embodiment illustrated in the drawings referred to hereinafter.

In addition to providing a structure which can be standardized in the manner mentioned above, I provide a cleaner which is of large capacity in proportion to its size and which is capable of operating continuously for long periods of time without any attention.

The cleaner which I provide is also of such

character that the upward flow of gas within the cleaner is interrupted so that liquid which is entrapped in the gas may be effectively taken therefrom and returned to the pool of liquid in the cleaner. This feature of the present invention is of substantial importance in cleaners of the character mentioned above as it is highly desirable that such cleaners be capable of operating without any attention for long periods of time. 5 If provision is not made for eliminating substantially all of the entrapped liquid from the gas during its passage through the cleaner the structure cannot operate over a long period of time without replacement of the contacting liquid. 10 This feature of the invention will be more specifically described hereinafter.

Other advantageous features of the cleaner which I provide will be apparent to those skilled in this art from the ensuing description of a preferred embodiment thereof.

In the accompanying drawings I have shown for purposes of illustration only a preferred embodiment of my invention.

In the drawings,

25 Figure 1 is an elevational view of a cleaner embodying my invention;

Figure 2 is a vertical section through the outer shell or container of the cleaner illustrated in Figure 1;

30 Figure 3 is a top plan view of the top cover of the cleaner illustrated in Figure 1;

Figure 4 is a section taken along the line IV—IV of Figure 3;

35 Figure 5 is an elevational view, partly in section, of the cartridge cleaner embodied in the structure shown in Figure 1;

Figure 6 is a top plan view of the structure shown in Figure 5;

40 Figure 7 is a partial section taken along the line VII—VII of Figure 5;

Figure 8 is a partial section taken along the line VIII—VIII of Figure 5;

Figure 9 is a partial section taken along the line IX—IX of Figure 5; and

45 Figure 10 is a section taken along the line X—X of Figure 5.

As shown in the drawings, the cleaner which I provide embodies a container or outer shell 2, a top cover 3 and a cleaning unit or cartridge 4, the 50 cartridge 4 being mounted in the shell 2 and being supported by the cover 3 in the manner described hereinafter. The cover is provided with an inlet opening 5 and an outlet opening 6 through which the gas enters and leaves the cleaner. The gas 55 enters the cleaner through the inlet 5 and passes downwardly around the cartridge 4 and then up through the cartridge and out of the cleaner through the outlet opening 6.

The container 2 may be a section of a circular 60 pipe of whatever thickness is needed to withstand the pressure or it may be a tank made specially for the purpose. The container is provided with a bottom 7 which closes off one end thereof. This bottom 7 will, of course, be made sufficiently thick 65 to withstand the pressures encountered in operation and will be tightly secured to the side walls of the shell by welding or any other suitable method. At the upper end, the shell 2 is connected by welding or otherwise to a flanged coupling member 8 which is provided with bolt holes 9 for bolting it and the cover 3 together. The cover 3 is likewise provided with bolt holes 10 corresponding with the bolt holes 9 and bolts 11 are passed through these openings and the 70 flanged coupling 8 and the cover 3 securely fas-

tened together by means of the nuts 12 which cooperate with the threaded ends of the bolts. While the cover 3 is shown attached to the shell by bolts, any suitable type of connection which is capable of withstanding the pressures employed may be used. For example, the cover 5 may be welded directly to the container or shell 2 and the flanges eliminated. Of course, an arrangement of this character would not permit as ready separation of the shell 2 and the cover as 10 is possible where the parts are merely bolted together.

The shell or container 2 is provided with an opening 13 near the base thereof to permit removal of the contacting liquid and any solid material which has been deposited in the container. This opening 13 is closed under ordinary operating conditions by a plug 14 threaded in a sleeve 15 which is welded or otherwise secured to the shell around the opening. The opening 16 is located higher on the shell 2 and is for the purpose of draining and refilling the shell. This opening is provided with an elbow 17 threaded in a sleeve 18 which is welded to the shell around the opening. The elbow 17 is positioned so that the end 19 extends upwardly so as to facilitate filling the shell with the contacting liquid. This elbow is provided with a plug 20 which normally closes the upper end thereof. When the cleaner is filled with the contacting liquid it is preferably filled 30 to approximately the top of the elbow so that the surface 21 of the pool of liquid will be adjacent the ends of the contactor tubes carried by the cartridge.

The cover 3 is a circular plate of sufficient thickness to withstand the pressures encountered and also to support the cartridge 4. It is provided with an inlet pipe 22 which is welded to the cover around the inlet opening 5 and an outlet pipe 23 welded around the outlet opening 6. To the bottom side of the cover 3 three stud bolts 24 are secured for the purpose of holding the cartridge 4 firmly to the cover. The ends of these bolts are threaded to receive nuts 25 on which the cartridge rests.

The cartridge 4 is preferably cylindrical and is provided with a side wall or jacket 31, a bottom 32 and a top 33. The bottom 32 and the top 33 are secured to the jacket tightly so that gas will not enter the cartridge without passing through the contactor tube 34 and will not pass out of the cartridge except through the outlet neck 35. The neck 35 is secured to the top 33 and extends upwardly therefrom and into a recess 36 in the cover 3. The neck fits tightly in the recess 36 so as to provide substantially a liquid-tight joint between the neck and the cover.

The entire cartridge is supported by the cover 3 through the bolts 24. These bolts extend downwardly from the cover through holes 37 in the wings 38 which are integral with the neck 35. It is obvious that with these three bolts and the three wings the cartridge as a whole may be secured in a rigid manner to and supported from the cover and in such a manner that the outlet 65 of a cartridge communicates directly with the outlet 6 in the cover.

The bottom of the cartridge contains several openings. The opening 39, which is located substantially axially of the cartridge, is for the 70 purpose of permitting liquid collected on the top of the bottom of the cartridge to return to the pool. One end of a tube or pipe 40 is secured to the periphery of the opening 39 and extends downwardly from the cartridge so that when the 75

cartridge is in position in the shell 2 the bottom end of this pipe 40 will be considerably below the pool level 21. The bottom 32 also contains openings 41 through which the contactor tubes 34 extend. Each contactor tube is secured to and supported by the bottom 32 and the upper end of each contactor extends into the interior of the jacket to a sufficient extent to prevent liquid deposited on the bottom 32 from returning to the pool through the contactor tubes. The upwardly extending ends of each tube also provide a support for a cap 42. The contactor tubes extend downwardly from the bottom of the cartridge to a position adjacent the pool level 21.

When the device is not in operation the lower edge 43 of each contactor tube is preferably slightly below the pool level but in operation the liquid around the tube is depressed so as to permit the passage of gas upwardly therethrough.

By the expression "contactor tube" as used in this specification I refer to a tube of the character disclosed in the Sillers Patent No. 2,048,145 which is utilized to effect an intimate contact between the liquid and the gas by virtue of the pressure of and the velocity at which the gas strikes the pool of liquid and passes upwardly through the tube. As is specifically described in said Sillers patent, a very substantial quantity of liquid is carried up into and through the contactor tube, and during the passage of the gas therethrough a very intimate mixture of the fluids is effected.

The jacket 31 of the cartridge houses apparatus for removing drops of liquid that may be carried up with the gas and for returning such liquid to the bottom of the cleaner. After the gas passes out of the upper end of a contactor tube it impinges upon and passes through the screen 44 of a strainer-like cap 42 carried at the upper end of the tube. The screen 44 may be made of wire or gauze or any other suitable material. The gas and liquid pass through the screen with a substantial horizontal component to the velocity thereof which prevents the larger drops of liquid from being carried up through the jacket with the gas to a greater height. This arrangement is especially effective in a device where the diameter is small and the distance between the strainer or cap and the wall of the cartridge is not great. These screens are not provided at the upper end of each contactor tube for catching solid material but are for the purpose of directing the spray which passes up through the contactor tubes laterally instead of vertically.

In spite of the use of strainners of the character just described or any other arrangement for a like purpose, fine drops of liquid are carried upward with the gas and it is necessary to remove them and return them to the supply of liquid in the bottom of the device in order to prevent depletion of this supply. Unless appropriate apparatus is provided to remove the drops of liquid from the gas the apparatus cannot operate uninterruptedly for any long period of time without replacement of the contacting liquid.

In the arrangement shown in the drawings, the gas passes upwardly through the jacket 31 and through one or more beds of filtering material. These beds of filtering material extend completely across the jacket so that the gas in its upward flow must contact the filtering material and pass therethrough. As the gas passes through the filtering material the entrained liquid is deposited on it and from there is returned to the pool in the bottom of the shell or container. Any suitable filtering material may be used. Where the gas being cleaned is natural gas crimped copper wool is satisfactory but any other material of similar physical character can be used so long as it is not detrimentally affected by the gas and oil or other contacting liquid.

Where the cleaning apparatus is designed to have a relatively large capacity measured in volume of gas passed through it in proportion to its size, the velocities employed are frequently so high that the liquid collected on the filtering material will not drain downwardly but will be blown up through the filtering material. This is particularly true where the velocity of the gas passing upwardly through the filtering material is relatively uniform throughout substantially the entire cross-sectional area thereof and where the liquid is collected on the filtering material in considerable quantities. I have found that this difficulty can be obviated by providing means to interrupt the flow of the gas in certain parts of the device and means for collecting the liquid and returning it to the pool of contacting liquid in the base of the device.

In order to interrupt the flow of the gas and collect the entrained liquid the device shown in the drawings is provided with two sets of spaced inclined radial troughs 46. In some instances only one set of radial troughs will be used whereas in other instances a greater number will be used. The upper end of each trough 46 is welded or otherwise rigidly secured to an annular supporting ring 47 which is secured to the inner wall of the jacket 31. The lower end of each radial trough is rigidly secured to the cone-shaped basin 48 secured to the upper end of a pipe 49. The pipe 49 extends downwardly through the jacket 31 and through the opening 39 in the bottom thereof and extends further downwardly inside the tube or pipe 40. The basin 48 and the pipe 49 are for the purpose of returning to the pool liquid which has been eliminated during the passage of the gas through the filtering material.

The troughs 46' of the second set are mounted in a manner similar to the troughs 46 included in the lower set. The upper end of each trough 46' is secured to the annular ring 50 which is secured to the inner wall of the jacket and the lower end of each trough 46' of this set is secured to a basin 51 which is rigidly secured to the upper end of a pipe 52 which extends downwardly through the jacket. This pipe 52 passes through the basin 48, the pipe 49, the opening 39 in the bottom of the cartridge and the pipe 40 and is for the purpose of returning to the pool any liquid which has been taken out by the filtering material positioned above the upper troughs 46. The troughs 46 and 46' not only carry the liquid to the basins 48 and 51 but they also serve to interrupt the upward flow of gas and materially reduce the velocity thereof.

Immediately above each set of troughs and resting thereon are conical wire screen baskets 53 which support the filtering material. Each bed 54 of filtering material carried by the wire baskets 53 is of substantial depth and the material is so placed that it will have a level upper surface. Each bed 54 is held in place by a circular wire screen 55 supported on an annular ring 56 mounted on the inner side-wall of the jacket. Each screen 55 is secured to an annular ring 56 and the annular rings are secured to the side-

wall of the jacket so that the filtering material will not be displaced during shipment.

Where it is desirable to use beds of filtering material which are of substantial depth I prefer 5 to split up the beds into sections. This arrangement is shown in the drawings. Immediately above each screen 55 there is another bed 57 of filtering material. These beds rest on the displacement preventing screens 55 and are held in 10 place by similar screens 58 which are likewise supported on annular rings 59 on the inner wall of the jacket.

The annular ledges or brackets on which the 15 various screens or troughs are supported act as baffles to deflect the gas flow along the walls inwardly toward the center of the device and thereby aid in rendering the filtering material effective.

As the gas passes upwardly through the jacket 20 the velocity thereof between the spaced troughs is frequently sufficiently high to prevent liquid from draining down. The velocity immediately above the troughs is nil and a short distance above the troughs is still quite small. By varying 25 the velocities of the upwardly moving gas at spaced points around the cartridge the gas will pass on upwardly through the filtering material but the liquid will be removed by said material and will flow with a lateral and generally downward component toward the troughs 30 where it is collected.

The space within the cartridge above the filtering material in the upper basket is unobstructed and communicates freely with the outlet 35 pipe 35 which in turn communicates with the outlet pipe 23.

In operation the gas enters the outer shell 2 of the cleaner through the inlet pipe 22 and the inlet opening 5 in the cover and passes 40 downwardly around the jacket. The gas strikes the pool of liquid in the base of the container 2 and then passes upwardly through the contactor tubes into the interior of the jacket. The gas passing up through the contactor tubes will 45 carry some liquid upwardly in the form of a fine spray. Most of this liquid which is carried up through the tubes will accumulate above the bottom 32 and will run back into the pool through the pipe 40. This liquid will carry with it 50 most of the dirt washed out of the gas. Some liquid will pass on upwardly through the jacket and will be caught on the filtering material in the lower basket. This liquid will flow into the basin 48 and will then be returned to the pool 55 through the pipe 49. A still smaller amount of the liquid entrapped by the gas will be caught by the material in the upper basket and this liquid will drain into the basin 41 and be returned to the pool in the basin of the device 60 through the tube 52.

The resistance to the flow of gas up through the contactor tube and through the material in the several baskets will not be great and will amount only to a few inches or a foot of the 65 total head. The elevation at which the liquid in each of the spaces between the several pipes which lead it back to the pool will stand above the liquid level which will be established in the container 2 will depend upon the pressure lost 70 in each operation, the liquid standing a little higher in each of the three pipes as one progresses toward the center pipe.

In most of the installations where a cleaner of this type is used the material to be removed 75 from the gas is finely divided particles of dust or

finely divided liquid particles such as tar. The embodiment shown in the drawings is not intended to be used to remove any volatile constituent from the gas or to add a volatile constituent thereto, so that the volume of the liquid will remain almost constant for a considerable period of time unless some of the liquid is carried over as a spray or mist with the flowing gas. This apparatus is particularly effective to prevent any substantial carry-over and should be 10 of such a size and operated at such a rate of speed that the carry-over will not be serious. Of course, if the volume of gas passed through the apparatus is greater than it can properly take care of, there will be a sufficient liquid 15 carry-over to prevent the device from being as effective as when used under proper conditions.

There are conditions where the gas is of such character or at such temperature that it tends to absorb some material from the oil or other 20 liquid being used or to give up some constituents to the liquid so that the volume of liquid may tend to increase or to diminish. The invention described above can be used under such conditions when appropriate additional features 25 which are well known in the art are added thereto in order to maintain the character and quantity of the liquid employed sufficiently constant for all practical purposes. It will be readily apparent that the device shown in the drawings 30 can be utilized with other equipment which will regulate continuously or intermittently the level of the liquid in the contactor so as to compensate for any carryover or increase in volume.

In the device shown in the drawings the cartridge is not on the center line of the container 35 2. One reason for this is that it is desirable to keep the apparatus as small in diameter as practicable and still provide connections for the admission and withdrawal of gas through the cover. In order to obtain proper connections 40 it is more convenient not to have the cartridge on the center line. A second reason is that it is desirable not to obstruct the inflow of gas through the inlet pipe any more than is necessary. As the space above the container required to insert the inlet and outlet pipes is limited, it is necessary to have the inlet pipes partially over the cartridge cover. It is preferable to have it overlap the cartridge cover as little as possible 45 in order to leave the flow unobstructed. This can be best accomplished by positioning the cartridge off center.

While I have shown and described a preferred embodiment of my invention it will be understood 55 that it is not limited to the specific apparatus shown and described but may be otherwise embodied within the scope of the appended claims.

I claim:

1. Contacting apparatus for cleaning gas under pressure comprising a pressure resisting container adapted to hold a pool of liquid, a top closure for said container, an inlet for admitting gas to the container above the level of the liquid therein, a substantially gas-tight cartridge supported in said container by the closure therefor, at least one contactor tube opening through a wall of the cartridge and extending downwardly to a point adjacent the surface of the pool of contacting liquid for permitting gas to pass from the container into the cartridge and for effecting intimate contact between the gas and the liquid, a gas outlet opening through a wall of the container and opening into the cartridge for discharging gas from the device, separating means 60 65 70 75 80 85 90 95 100 in the cartridge including a bed of filtering material extending transversely across the cartridge between the contactor tube and the outlet and a plurality of spaced radially disposed drainage members positioned below the filtering bed for varying the rate of flow of gas through the bed of filtering material, and means cooperating with said drainage members for returning liquid removed from the gas to the pool in 10 said container.

2. In gas cleaning apparatus of the character described, the combination of a substantially gas-tight enclosure, means for passing gas upwardly through said enclosure, an outlet for discharging gas from the enclosure, a bed of filtering material filling a transverse section of said enclosure between the inlet and outlet, said bed having an inclined bottom, a plurality of spaced inclined troughs disposed adjacent the bottom 15 of said bed and in the path of the gas travelling 20

therethrough, and a duct communicating with the lower end of each of said troughs and extending downwardly through said enclosure.

3. In gas cleaning apparatus of the character described, the combination of a substantially gas-tight enclosure, means including an inlet at one end and an outlet at the other end of said enclosure for passing gas upwardly through the enclosure, a bed of filtering material extending completely across a traverse section of said enclosure, supporting means for said bed, a plurality of spaced inclined troughs disposed adjacent the bottom of said bed and in the path of the gas as it enters said bed, and a discharge conduit communicating with the lower end of each of said troughs and extending downwardly through said enclosure, whereby entrained liquid will be removed from the gas and discharged from the enclosure.

EDWIN R. BRODEN. 20
